(57) **CLAIM**

The ornamental design for a picture holder, as shown and described.

DESCRIPTION

FIG. 1 is a front perspective view of a picture holder, showing my new design;

FIG. 2 is a rear perspective view of FIG. 1;

FIG. 3 is a front elevational view of FIG. 1;

FIG. 4 is a rear elevational view of FIG. 1;

FIG. 5 is a left-side elevational view of FIG. 1;

FIG. 6 is a right-side elevational view of FIG. 1;

FIG. 7 is a top plan view of FIG. 1;

FIG. 8 is a bottom plan view of FIG. 1;

FIG. 9 is an exploded perspective view of FIG. 1;

FIG. 10 is an exploded left-side elevational view of FIG. 1; and,

FIG. 11 is an exploded top plan view of FIG. 1.

The broken lines showing a photograph of a pet in the figures depict environmental matter and form no part of the claimed design. The broken lines in FIGS. 1-11 showing a stem depict portions of the picture holder that form no part of the claimed design.

1 Claim, 9 Drawing Sheets
